TADEUSZ LAMPE AND FELIKS PRZECIECHOWSKI, OF WARSAW, RUSSIA.

BOTTLE-WASHING MACHINE.

1,203,365.

Specification of Letters Patent. Patented Oct. 31, 1916.

Application filed April 9, 1914. Serial No. 830,734.

To all whom it may concern:

Be it known that we, TADEUSZ LAMPE and FELIKS PRZECIECHOWSKI, subjects of the Czar of Russia, and residing at Warsaw, Russia, have invented certain new and useful Improvements in Bottle-Washing Machines, of which the following is a specification.

Our invention relates to a bottle washing machine for cleansing bottles within and without, from dirt adhering thereto, by means of rinsing liquids.

A construction of the apparatus embodying the invention is shown by way of example in the accompanying drawing, in which,

Figure 1 is a view partly in transverse section and partly in end elevation of an apparatus embodying the features of the present invention. Fig. 2 is a fragmentary section taken on the plane indicated by line 2-2 of Fig. 1. Fig. 3 is a top plan view of the parts seen in Fig. 1, parts being seen in horizontal section.

The compartments *a* (Fig. 2) of any length are formed by axially extending flat plates *q* lying at radially spaced intervals, the said plates being connected by means of bars *u* to rings or plates *t*, *t*. The so formed and strengthened annular body is connected by radial arms *b* with a hub *v* in such a manner that the hub *v* and the arms *b* and the said annular body form together a wheel or carrier. The hub *v* is keyed to a shaft *c*, revoluble in bearings *p* of a casing *o*, surrounding the carrier and serving at the same time as a liquid receptacle.

The casing or liquid receptacle *o* is formed by two parts the upper part being detachably fixed to the lower part by means of screws or the like. The carrier is rotated in any suitable manner, for instance, by means of a mechanically driven disk *r* mounted in bearings *r'* fixed to the casing *o*. Keyed to the free end of the rotatable shaft of the disk *r* is a crank *r'*, the end of which is pivotally connected with a link *l'*, the other end of which is rotatably held by an arm *n*, rotatably mounted on the said shaft *c*. A further arm *l''* is pivotally connected to and held by the arm *n* and passes through an aperture in the casing *o* and is provided with a pawl, the latter engaging teeth *s* formed on one of the outer rings *t* of the said annular body and rotating thereby the body in the direction indicated by the

arrow when power is applied to the disk *r*. Mounted on the inner side of the receptacle *o* is a spring actuated pawl *m*.

A ring *d* is stationarily mounted at a short distance from and fixed to the one end wall of the apparatus, said ring being formed with an aperture opposite to an opening *e* in the side wall of the receptacle. Before the opening *e* an inclined chute *g* is provided. A further inclined wall *h* is attached to the casing *o* at the opposite side beneath an opening *f* therein, the lower end portion of the wall *h* being formed as a trap.

The bottle *i* to be cleaned is placed upon the inclined feeding plate *g*, drops in through the opening *e* into the section located in front thereof, and is carried away in the direction indicated by the arrow (Fig. 2). Now the bottle is shifted automatically laterally to the right in the compartment by the inclined cam terminal of the ring *d*, and at the same time uniformly rotated about its axis, incidentally enhancing the cleansing function, and finally occupies the position indicated by *l*. At the same time the bottle *k* located at the extreme right hand end is forced, owing to the lateral pressure exerted by the other bottles in the section, to pass through the opening *f* and drops into the trap *h*. During the continuous rotation of the wheel the bottle *i* travels in the compartment, from the left hand to the right hand, is submerged in the liquid, is filled with the latter, reaches the level of the opening *e* is shifted to the right to the extent of its diameter by the bottle inserted next, attains the position indicated by *l*, is emptied and travels in the described manner, remaining always in the same compartment, through the positions 3, 4 and so on, until 8, and finally attains the position of the bottle *k* after it has been filled and emptied several times, whereupon it is thrown out of the compartment into the trap *h*.

From the foregoing description and drawings of this application it will be obvious that in the operation of this device the cam terminal *d'* of the annular ring member *d* bears a distinctly advantageous relation to the intake point of the casing, the cam being of a throw equal to the diameter of a bottle so that substantially as one bottle is entering the compartment just opposite the intake opening another bottle will be discharged automatically from said compartment through the opening in the casing at

the opposite side thereof. It will be apparent that the incoming bottle is rotated by its frictional contact with the cam d' and that the other bottles are rotated by contact with said incoming bottle. The formation of the chute g on an incline enables the bottles to be fed automatically while being stacked on this chute and allowed to roll down into the carrier as the unoccupied space is presented. The annular member or ring d in rear of the intake opening constitutes means for retaining the bottles in the successive compartments of the carrier against movement in the direction of occupying the excess space in the respective compartment exposed at the point of the intake opening. Thus it is that the newly supplied bottle is in excess of the number of bottles which the carrier is capable of accommodating, resulting in the lateral ejection of the bottle, from the discharge end of the compartment, which has been longest in the carrier. In performing this function it is quite obvious that the bottles are caused to rotate, as hereinbefore premised, into and out of position. It is further to be particularly noted that the discharge opening of the casing is located in advance of the plane of the intake opening and, of course, at the opposite side of the carrier, a distance approximately equal to the dimension of a compartment in a circumferential direction, the intake opening itself being disposed above the lower portion of the casing of the apparatus.

In carrying out the construction of the device it is desirable that each of the compartments which extend axially of the carrier should be of a length in an axial direction equal substantially to a multiple of the diameter of the bottles to be washed, this insuring the physical contact of the bottles one with the other and preventing likelihood of breakage in the rolling operation described with reference to the discharge of the bottles successively from the machine.

Having now particularly described and ascertained the nature of our said invention and in what manner the same is to be performed, we declare that what we claim is:

1. In bottle washing apparatus, the combination of a carrier, means dividing said carrier into radial compartments, a confining casing disposed to prevent displacement of bottles in the compartments axially of said carrier, each of the compartments being of a length, axially of the carrier, equal substantially to a multiple of the diameter of the bottles to be washed, a feeding opening being formed in the casing for the admission of bottles laterally one at a time to the successive compartments, means for moving the carrier for causing the compartments to successively pass the feeding opening, and ejecting means in advance of the feed-

ing opening and in the path of each freshly fed bottle disposed to shift such bottle and all contained bottles in the respective compartment axially of the carrier the distance equaling the diameter of a bottle, a discharge opening being formed in the casing substantially in the plane of the ejecting means at the opposite end of the casing from the feeding opening.

2. In bottle washing apparatus, the combination of a carrier, means dividing said carrier into radial compartments, a confining casing disposed to prevent displacement of bottles in the compartments axially of said carrier, each of the compartments being of a length, axially of the carrier, equal substantially to a multiple of the diameter of the bottles to be washed, a feeding opening being formed in the casing for admission of bottles laterally, one at a time to the successive compartments, means for moving the carrier for causing the compartments to successively pass the feeding opening, ejecting means in advance of the feeding opening and in the path of each freshly fed bottle disposed to shift such bottle and all contained bottles in the respective compartment axially of the carrier the distance equaling the diameter of a bottle, a discharge opening being formed in the casing substantially in the plane of the ejecting means at the opposite end of the casing from the feeding opening, and a chute for directing bottles into the feeding opening and for sustaining a supply of bottles in position for moving by gravity laterally into said feeding opening.

3. In bottle washing apparatus, the combination of a carrier, means dividing said carrier into radial compartments, a confining casing disposed to prevent displacement of bottles in the compartments axially of the carrier, each of the compartments being of a length, axially of the carrier, equal substantially to a multiple of the diameter of the bottles to be washed, a feeding opening being formed in the casing for the admission of bottles laterally one at a time to the successive compartments, means for moving the carrier for causing the compartments to successively pass the feeding opening, and ejecting means in advance of the feeding opening and in the path of each freshly fed bottle disposed to shift such bottle and all contained bottles in the respective compartment axially of the carrier the distance equaling the diameter of a bottle, a discharge opening being formed in the casing substantially in the plane of the ejecting means at the opposite end of the casing from the feeding opening, the feeding opening being above the lower portion of the casing and the discharge opening being above the plane of the feeding opening a distance approximately equal to the di-

dimension of a compartment in a circumferential direction, said lower portion of the casing being adapted to contain a cleansing fluid.

- 5 4. In a bottle washing apparatus, the combination of a carrier, means dividing the carrier into compartments, means for rotating the carrier, an intake opening for delivering bottles to the compartments in a direction axially of the carrier, a discharge opening in advance of the plane of the intake opening and at the opposite side of the carrier, a cam substantially in the plane of the discharge opening 10 for ejecting bottles from each compartment successively incident to the presence of a bottle in excess of the carrying capacity of

the respective compartments beyond the cam, the actual carrying capacity of each compartment being one bottle in excess of 20 the last-named capacity, and means in the rear of the intake opening for retaining contained bottles in successive compartments against movement in the direction of occupying the excess space in the respective compartments exposed at the point of the intake opening. 25

In testimony whereof we affix our signatures in presence of two witnesses.
